UNITED STATES PATENT OFFICE

CHARLES TURNER JONES, OF LEICESTER, ENGLAND, ASSIGNOR TO UNITED SHOE MACHINERY CORPORATION, OF PATERSON, NEW JERSEY, A CORPORATION OF NEW JERSEY

TREADLE MECHANISM

Application filed August 28, 1931, Serial No. 559,881, and in Great Britain September 16, 1930.

This invention relates to improvements in mechanism for controlling the operation of machines of the type which are usually operated by an operator standing at the machine and controlling the operation of the machine by means of foot-operated controlling levers.

In the operation of machines of the type disclosed in United States Letters Patent No. 786,190, granted March 28, 1905 on application of Louis A. Casgrain, for example, it has been necessary for the operator to stand up for long periods which causes fatigue to the operator with the result that at the end of the day (or working period) there is a marked decrease in the production of the operator and in the quality of the work produced.

One of the objects of the present invention is to provide a mechanism for controlling the operation of a machine the use of which will prevent or minimize fatigue to the operator.

One feature of the invention, accordingly, resides in a mechanism for controlling the operation of a machine having a foot-treadle secured to the lower portion of the base of the machine, a bracket secured to the machine base, a second foot treadle pivoted to said bracket and located above said first-mentioned foot treadle, and connections between the treadles including a lever actuated only by the upper treadle whereby an operator may control the operation of the machine from a plurality of positions, said treadles being so arranged that the use of one of the treadles is not interfered with by the other treadle. Preferably and as illustrated the machine is provided with the usual foot-operated treadle or treadles and with an auxiliary treadle or treadles located above the usual treadles of the machine in such position that the operator, when seated in front of the machine, for example, on a high stool, may use the auxiliary treadle to control the operation of the machine.

The illustrated treadle mechanism may be applied to machines of the type disclosed in the above-mentioned Letters Patent, or to other machines wherein the operation of the machine is controlled through foot-oper-

ated treadles, without any change being made in the machines. The treadle mechanism is so arranged and located with respect to the usual foot-operated controlling treadles that the operator may conveniently operate a machine provided with the illustrated treadle mechanism through the usual treadles while he is in a standing position.

With the above and other objects in view the invention will now be described with reference to the accompanying drawings and pointed out in the claims.

In the drawings,

Fig. 1 is a side elevation of one form of the mechanism and of a part of a machine to which the mechanism may be applied;

Fig. 2 is a plan view of the mechanism; and

Fig. 3 is a view in side elevation illustrating the position of an operator when sitting down to operate the machine.

Referring to Fig. 1, there is shown a slugging machine having a base 10 and column 12. The head of the machine is provided with a stopping and starting mechanism for controlling the operation of the fastening-inserting mechanism of the machine. The machine is also provided with the usual foot-operated treadle 14 which is connected to the starting-and-stopping mechanism by a rod 16. A second foot-operated treadle 18 is also provided for lowering the horn and horn tip 20 to allow for the presentation of work to the machine. For a more detailed description of the machine, reference may be had to the above-mentioned Letters Patent.

The mechanism for operating the machine while the operator is in a sitting position will now be described. A treadle 22 is placed in such a position that the operator while sitting in front of the machine can comfortably rest his foot on the treadle and operate it to start and stop the machine. A chair 24 is provided on which the operator sits. The chair is arranged relatively to the front of the machine and heightwise in the most convenient position for the particular operator of the machine.

The seat of the illustrated chair is about thirty-three inches from the floor and the front of the seat is about seven inches in front

of a vertical line through the center of the horn tip of the machine. These dimensions, however, will naturally depend both on the dimensions of the machine and the size of the operator. The chair has a back rest 26 arranged in the most suitable position to support the back of the operator. The height of the chair may be varied in any suitable manner in accordance with the height of the operator.

The treadle 22 is pivoted at 28 to a bracket 30 which is fixed to one of two vertical parallel bars or arms 32, 32 connected together at their upper ends by a bolt or cross bar 34 and fixed at their lower ends to the base 10 at the rear of the column 12. Stay bars 36, 36 are fixed at their lower ends to the base 10 by means of a pin 37 which also forms a fulcrum for the treadle lever 14. The upper ends of the stay bars 36 are connected to the bars 32, 32 thus holding the bars 32 rigidly in position. A block 38 is adjustably fixed to the forward portion of the treadle 22. The heel of the operator rests against the block 38 and the position of the block may be varied in accordance with the requirements of the particular operator. As shown in Fig. 3, the forward end of the treadle 22 does not extend forwardly of the base 12 and accordingly does not interfere in any way with the operation of the machine by the treadle 14.

The rear end of the treadle 22 is pulled down about its pivot by a spring 40 connected at one end to an arm 41 extending rearwardly from the treadle 22 and at the other end to one of the vertical bars 32. The movement of the treadle 22 under the influence of the spring is limited by a stop screw 44 fixed in the bracket 30. A lever 46 is pivoted on the bolt 34 and one arm of this lever extends under but not quite in contact with the treadle 22. A plate 48 fixed on the treadle 22 is engaged by the forward end of the lever 46 when the treadle is depressed, the plate acting to prevent wear on the bottom surface of the treadle. The other end of the lever 46 is forked, as shown in dotted lines in Fig. 2, and engaged beneath a block 50 which is adjustably fixed on the rod 16 by a set screw 51. A rest 52 for the left foot of the operator is arranged at the left-hand side of the machine and this rest is fixed by a bracket 54 to one of the stays 36 and by a bracket 56 to the base 10.

The treadle mechanism just described was developed particularly for use when the machine is employed for slugging loose heels, though obviously it can be used under other conditions. The machine, as is usual, stops with the horn lowered sufficiently to enable the operator to insert a heel between the horn tip 20 and the usual guard plate of the machine so that when operating upon loose heels it is unnecessary to lower the horn by means of the treadle lever 18. In his sitting position

the operator can readily pick up a heel with his right hand and present it to the machine. He can then start the machine by means of the treadle 22 and when the operation upon the heel is completed he can take it from the machine with his left hand and place it in a suitable receptacle without changing his position. The chair has extending from it a bar 58 on which the operator may rest his foot to give him a small change in position. The operator may work alternately in a sitting or standing position and this change is readily made by merely moving the chair toward or away from the machine.

If it is desired to lower the horn for the presentation of work to the machine when the operator is sitting down, the foot rest 52 may be pivoted to the machine base and may be connected to the usual horn-lowering mechanism. The operator in his sitting position can then control with his feet both the starting of the machine and the lowering of the horn.

Having thus described my invention, what I claim as new and desire to secure by Letters Patent of the United States is:

1. A mechanism for controlling the operation of a machine having, in combination, a foot treadle pivoted to the lower portion of the base of the machine, a bracket secured to the machine base, a second foot treadle pivoted to said bracket and located above said first-mentioned foot treadle, and connections including a lever located between the upper treadle and the lower treadle and actuated only by the upper treadle whereby the operator may control the operation of the machine through either treadle.

2. A mechanism for controlling the operation of a machine having, in combination, a treadle lever pivoted to the lower portion of the base of the machine, a bracket secured to the machine base, a second treadle lever pivoted to said bracket and located above said first-mentioned treadle lever, and connections between the two levers including a substantially horizontal lever cooperating only with said second treadle lever whereby an operator may control the operation of the machine through either treadle lever.

3. A treadle mechanism for controlling the operation of a machine having, in combination, a rod adapted to be moved to control the operation of the machine, a treadle lever pivoted to the base of the machine and connected to said rod, said treadle lever being adapted to be operated when an operator is in a standing position, a substantially horizontal lever pivoted above said treadle lever, and a second treadle lever connected to said rod by said horizontal lever and adapted to be used to control the operation of the machine through said lever when the operator is in a sitting position.

4. A treadle mechanism for controlling the

operation of a machine having, in combination, a rod adapted to be moved to control the operation of the machine, a treadle lever pivoted to the base of the machine and connected to said rod, said treadle lever being near the floor and thereby adapted to be operated when an operator is in a standing position, a substantially horizontal lever pivoted above said treadle lever, and a second

10 treadle lever located substantially further from the floor than the first treadle lever and pivoted above said horizontal lever, said second treadle lever being connected to said rod by said horizontal lever and being adapted 15 to be used to control the operation of the machine when the operator is in a sitting position.

5. A treadle mechanism for controlling the operation of a machine having, in combination, a treadle mounted on the lower portion of the base of the machine, a rod connected to the treadle for controlling the operation of the machine, a pair of supporting arms secured to the machine base, a cross-bar connecting the arms at their upper ends, a second treadle mounted on one of the supporting arms, a lever pivoted on the crossbar and adapted to be engaged by the second treadle when the treadle is depressed, and 30 means on the rod constructed and arranged to be engaged by said lever to control the operation of the machine.

6. In a treadle controlled machine, a treadle adapted to be operated by an operator when the operator is in a standing position, said treadle being pivoted to the base of the machine, a rod to which said treadle is connected, a pair of supporting arms rigidly connected to the machine base, a rod connecting the upper ends of said supporting arms, a bracket secured to one of said arms, a second treadle pivotally secured to said bracket and adapted to be operated when the operator is in a sitting position, a lever 45 pivoted to the rod connecting the upper ends of the supporting arms, and means on said first-mentioned rod adapted to be engaged by one end of said lever, the other end of said lever being adapted to be engaged by 50 said second treadle when the treadle is depressed.

7. A treadle mechanism for controlling the operation of a machine having, in combination, a treadle lever secured to the machine base and extending forwardly of the machine in a position where it may be depressed by an operator while in a standing position, a rod connected at one end to said treadle, supporting arms secured to the machine base, a 60 crossbar connecting the upper ends of said arms, a second treadle lever connected to one of said supporting arms, said treadle lever having its forward end terminating at a point to the rear of the front of the machine 65 base, and means connecting said second

treadle lever to said rod, said treadle levers being so located that the operation of the machine may be controlled by either lever without interference by the other.

8. A treadle mechanism for controlling the operation of a machine having, in combination, a treadle pivoted to the lower portion of a machine base and extending forwardly of the base of the machine, a rod connected at one end to said treadle and at its other end to an operating mechanism, a pair of supporting arms secured at their lower ends to the machine base, a crossbar connecting the upper ends of said arms, a bracket secured to one of said arms, a second treadle pivoted to said bracket, the forward portion of said second treadle extending substantially to the forward portion of the machine base but rearwardly of the forward portion of the first-mentioned treadle whereby either treadle 85 may be operated without interference by the other treadle, a lever fulcrumed on said crossbar and adapted to be engaged at one end by the second treadle when said second treadle is depressed, and means on said rod adapted to be engaged by the other end of said lever to raise the rod when the second treadle is depressed.

9. A treadle mechanism for a machine having, in combination, a pair of supporting arms secured to the machine base, a cross-bar connecting the upper ends of said arms, a bracket mounted on said cross bar, a treadle fulcrumed on said bracket, a lever pivoted on said crossbar and adapted to be engaged by the treadle when the treadle is depressed, and a vertical rod having means thereon adapted to be engaged by said lever and to be moved upwardly thereby to control the operation of the machine.

10. An auxiliary treadle mechanism for a foot controlling machine having, in combination, a bracket secured to the machine base, a treadle pivoted to said bracket and constructed and arranged to be operated by an operator seated at the front of the machine, a lever pivoted to said bracket and adapted to be engaged at one end by said treadle when the treadle is depressed, and means engaged by the other end of said lever, said means including a vertical rod constructed and arranged to be moved upwardly when the treadle is depressed thereby to control the operation of the machine.

In testimony whereof I have signed my name to this specification.

CHARLES TURNER JONES.
